STEAM GENERATOR

Alta E. Oeltjen and Ira W. Ford, Los Angeles,
Calif.

Application April 9, 1940, Serial No. 328,676

2 Claims. (Cl. 122—250)

Our invention relates to steam generators and, more particularly, to the "flash" type with a supply of boiling water and with means for quickly, efficiently and economically furnishing a supply of steam for utilization by hat-blocking, garment-pressing or other type of equipment or device.

An object is to provide a "flash"-chamber extension that is adjacent a burner, whose function is to convert into steam such water as may fall to be converted in the "flash" chamber.

Another object is to provide, in a "flash" steam generator, a novel baffle, disposed in the path of the incoming hot water to prevent it from reaching said equipment or device.

Further objects and advantages will become apparent in this specification and the accompanying drawing, in which—

Figure 1 is a vertical, sectional view of one of several possible forms of a generator embodying my invention;

Figure 2 is an elevation of the same, with a part broken away, taken in the direction of the arrow 2 of Figure 1.

The numeral 10 designated a vertical, cylindrical casing having suitable heat insulation (not shown) and being supported by legs 11.

Within casing 10 is a "flash" generator main assembly 12 comprising a spirally disposed coil of tubing 14, the intake end thereof being connected to a source of water supply 15. The discharge end of said coil is connected by sub-assembly 46 to a quick-acting valve 16, in turn connected to needle valve 17 provided with hand control 18, the needle element being indicated by 32.

Inside of the casing is a "flash" chamber constituted of a horizontally disposed, hollow, cross-like member 20; the interior of it being designated by 19; secured to the top thereof, is steam-outlet pipe 21, controlled by valve 22, the member-adjacent end of said pipe extending in part into the interior of said member 20 and has secured to it a novel baffle member 23, axially aligned with a pipe 24 depending from said member and with pipe 19a providing communication between interior 19 and valve 17. As can be seen, the baffle member consists of a T fitting adapted to receive steam from the "flash" chamber.

Located centrally within the casing 10, adjacent the lower end of coil 14, is a main burner 27 carried by a branch 28 of a gas supply pipe 29. Also carried by branch 28 is a supplementary burner 30 of the "buzzer" type, also referred to as a "buzzer," its open end terminating adjacent

burner 27 and adjacent extension tube 25, which as is seen is an extension of pipe 24 and extends downwardly therefrom axially through coil 14 and cross-sectionally is reduced relatively to pipe 24 and is closed by cap 26. Extension tube 25, because it is adjacent burner 27 and its flame 31 is referred to also as a burner-adjacent extension of coil 14.

The flow of gas to branch 28 is controlled by valve 45, which is carried by supply pipe 29. Valve 45 is provided with an arm 34, connected to a similar arm 35 of valve 16 by connecting rod 36 for simultaneous movement. Link 37, pivoted to arm 34, is connected to a suitable foot treadle 38, the treadle being pivotally secured to one of said legs 11, as is seen in Figure 2. A spring 39 secured to arm 35 retains arms 35 and 34 in the position shown in Figure 2, with the aid of stop lug 40.

The operation of the device is as follows: The coil 14 is provided with water therewithin, which by means of heating means or main burner 27 and buzzer 30 is normally kept at boiling temperature. Valve 45 normally is slightly open to allow a continuous supply of gas to the burners. When the treadle is depressed, valve 45 is fully opened, thereby causing main burner 27 to burn with a full flame and buzzer 30, normally burning with a low flame, to project a blast of flame extending as far as "flash"-chamber 19, the increased heat supplied by both said burners thereby corresponding to the increased flow of water into coil 14. When treadle 38 is depressed, valve 16 is opened, thereby permitting a flow of controlled hot water through needle valve 17 so as to produce steam of the desired degree of dryness. The hot water encounters baffle 23, whose temperature has now been considerably raised by the increased heat supply, and is converted into steam, which passed into the open ends 23a of T 23 and up, through pipe 21 to the device utilizing the steam. Any water dropping from "flash" chamber 19 into extension tube 25 is converted into steam because of the burner-adjacent or flame-adjacent disposition of said extension tube.

From the foregoing it is apparent that we have provided a simple, practical and efficient steam generator for the purposes mentioned. Particularly, has a novel form of baffle been provided for preventing water from entering the device utilizing the steam.

The particular form of our invention shown is merely illustrative and we reserve the right to make numerous changes in the dimensions, forms

and relative dispositions of the various parts within the scope of the appended claims.

We claim—

1. A steam generator comprising: a heating coil; at least two burners for heating said coil; an expansion chamber disposed over, connected to, and communicating with, said heating coil; an extension of said expansion chamber extending downwardly within said heating coil; one of said burners being located beneath said heating coil and adapted to heat said heating coil, and the other of said burners being disposed adjacent the lowermost end of said extension and directed toward said heating coil and said expansion chamber and adapted to supply a blast 15 of flame long enough to traverse said heating coil and terminate at said expansion chamber.

2. A steam generator comprising: a heating coil; at least two burners for heating said coil; an expansion chamber disposed over, connected to, and communicating with, said heating coil; 5 an extension of said expansion chamber extending downwardly within said heating coil; one of said burners being adapted to heat said heating coil, and the other of said burners being directed toward said heating coil and said expansion chamber adapted to supply a blast of flame long enough to traverse said heating coil and terminate at said expansion chamber.
